JOSEPH F. DIETRICH, OF GOLD HILL, NEVADA, ASSIGNEE TO PAUL HAHNEWALD, OF AVON, COLORADO.

DISCHARGE-SCREEN FOR CENTRIFUGAL GRINDING-MILLS.

1,053,416.

Specification of Letters Patent.

Patented Apr. 8, 1913.

Application filed August 26, 1912. Serial No. 717,006.

To all whom it may concern:

Be it known that I, JOSEPH F. DIETRICH, a citizen of the United States, residing at Gold Hill, in the county of Storey and State of Nevada, have invented a new and useful Discharge-Screen for Centrifugal Grinding-Mills, of which the following is a specification in such full and clear terms as will enable those skilled in the art to construct and use the same.

This invention relates to a screen for rotary grinding mills, and its object is to provide a mill with more efficient discharge of the pulp than is possible where the screens extend around the mill circumferentially.

It will be understood by those skilled in the art that with some of the rotary type such as Chilian, or other mills having a more or less circular pan that it is common to provide a series of circumferential screens for the discharge of the pulp from the mill. With such screens the tendency of the pulp is to circulate around the mill in waves rather than to discharge radially through the mill screens, the total screen area being comparatively less when considered with respect to materials circulating around the screen than would be the case if the materials impinged directly thereupon at an angle of 90°.

In this mill the screen is placed substantially radially to the body of the mill so that as the rolls cause the pulp to circulate around the mill it strikes the screens substantially at right angles thereto, thus effecting a greater discharge with a given screen area than is possible where the screens are placed circumferentially.

In the drawings in which the same numeral of reference is applied to the same portion throughout the several views, Figure 1 is a vertical sectional view through the mill having this screen applied thereto, Fig. 2 is a plan view of the mill, and Fig. 3 is a sectional view showing the screen and discharge trough of the mill.

The numeral 1 represents a suitable fixed base plate which has a trough 2 at the edge thereof for the discharge of the pulp and within which is the track die 3. Extending upwardly from the base plate is a suitable hollow support 4 upon which is revolvably mounted a frame 5. The frame 5 rotates upon a suitable bearing upon the hollow

support and the rollers 6 are provided with short shafts 7 which rotate within journal boxes on the frame 5. Above the frame 5 the hollow support is provided with a suitable collar 9 upon which collar is supported a bevel gear 10, said bevel gear having a suitable connection 11 with the frame 5 for turning the rollers.

Above the bevel gear there is a suitable support 11 having journal boxes 12 and 13 which support a shaft 15, said shaft having a small gear 16 in mesh with the large bevel gear.

The ore is fed into the mill through the hollow support by means of a suitable pipe 17. Above the base of the mill there is a suitably high cylindrical wall 19 to prevent the rolls from splashing the pulp over the top thereof. The base or pan upon which the track die is mounted has three walls 20, which extend spirally away from the track die and terminate at screens 21, there being three of said screens, each of which is placed substantially radially with respect to the track die. As the material is pulverized by the mill it is carried around and impinges substantially at 90° to the screens, thus effecting the greatest possible discharge of pulverized material and any material that fails to pass through the screens is at once washed back into the mill to be again operated upon by the next roll in turn.

The result of the foregoing construction is that the pulp passes around the mill in several waves, each of which waves is in turn brought to a full stop and compelled to start over again, thus effecting the maximum discharge of pulp through the screens.

It will be understood by those skilled in the art that while the mill shown is of the Chilian mill type, that these screens may be applied to any type of mill, as for example the mill having substantially vertical axes or the old time arrastra.

Having thus described my invention what I claim as new and desire to secure by Letters Patent of the United States, is as follows:

1. In a grinding mill, a pan, means to pulverize the ore placed in said pan, a series of radially extending screens, and substantially spiral walls leading to said screens from said pan, substantially as described.

2. In a grinding mill, a grinding pan, means therein to pulverize the ore placed in said pan, a plurality of screens extending radially around the pan, and a plurality of 5 substantially spiral walls leading from the pan to said screens, substantially as described.

In testimony whereof I have hereunto set my hand this 9th day of October, A. D. 1912, in the presence of two subscribed witnesses.

JOSEPH F. DIETRICH.
